HANS A. RING, OF MADISON, WISCONSIN, ASSIGNOR TO BURGESS BATTERY COMPANY, OF MADISON, WISCONSIN, A CORPORATION OF WISCONSIN.

APPARATUS FOR INSERTING DRY-CELL CORES INTO CANS.

Application filed June 18, 1926. Serial No. 116,852.

This invention comprises an improved method and apparatus for mechanically inserting dry cell cathode cores or bobbins into dry cell cans during the assembly operation.

5 My apparatus may be used as part of a machine designed to assemble flash light cells automatically. In the accompanying drawing, Fig. 1 is a front elevation of the assembly apparatus, partly in section; Fig. 10 2 is a plan view on the line 2—2, Fig. 1; Figs. 3 and 4 show the plunger in different positions; and Fig. 5 is a vertical section of an ordinary dry cell.

A cylindrical dry cell of the bag type is 15 shown diagrammatically in Fig. 5. It consists of a can 1, in which there is a core 2 comprising a carbon rod 3 surrounded by a depolarizing mixture of conductive carbonaceous material and a depolarizer, such 20 as manganese dioxide, conducting salts, and water. The core may be surrounded by a bibulous envelope 4 of cheesecloth, tissue paper, or hardened dip, such as is described in U. S. Patent No. 1,316,597, and may be insulated at the bottom by an attached paper 25 washer, or by folding the bibulous envelope across the bottom of the core, or by an insulating layer of paraffin or suitable wax 5. In lieu of the described bottom construction, 30 an insulating washer may be used at the bottom of the can, the core resting on this washer. A suitable gelatinous or pasty electrolyte 6 separates the core from the can. This electrolyte may be that described in 35 U. S. Patent No. 1,292,764 and may be compounded as described in U. S. Patent No. 1,370,056. An expansion space 7 is topped by a water proofed washer 8 supporting a wax or pitch seal 9.

40 My invention covers an improvement in the method of introducing the core into the can, by pushing the core against frictional resistance. In my improvement the frictional resistance is formed in part, at least, 45 by the can into which the core is introduced. This method not only simplifies the apparatus but it overcomes any tendency to break the insulating wax 5, when that core construction is used. Also the cores may vary 50 in diameter without interfering with the operation of the device.

The apparatus consists of a core holder 10 which operates like a human hand and can be mechanically moved up and down

by timing mechanism not shown in detail. 55

It has a spring-actuated hinged member 11 forming a jaw which opens slightly as a dry cell core 4 is pushed into place from an ordinary feeding dial 12, as shown in Fig. 2. The core may be inserted manually 60 or by a reciprocating pusher 13. The friction which holds the core in place in the jaw may be obtained by means of the compression spring 14 working against the hinged member 11, the swinging movement of which is controlled by an adjustable stop 15. Attached to the bottom of the hinged member 65 is a small finger 16 which can serve to deflect or thrust the core laterally.

The sequence of operations is as follows: 70 The core 4 is pushed into the jaw of the core holder while can 1 is being placed in position underneath and registering with the core (see Fig. 2). The can usually contains the requisite amount of liquid electrolyte 6. 75 The can must be held tightly enough to withstand the side pressure of the core while the latter is being lowered into the can. The plunger 17, which pushes the core through the core holder into the can, should be hollowed out so that its downward pressure does not come on the carbon rod 3, but comes on the body of the core. It may also be cut 80 away on the side toward pusher 13, as shown, to shorten its stroke and to allow the core to be pushed into the holder from that side as described. The core holder and plunger are so actuated that they start their downward stroke at the same time, the plunger 85 traveling at the higher speed. The core 90 holder stops at a point slightly above the can 1, (Fig. 3) with the finger 16 positioned inside the can. The plunger or ejector 17 then pushes the core from the jaw of the core holder into the can against the frictional 95 resistance of the jaw sides. As the core clears the jaw, finger 16, actuated through hinged member 11 by spring 14, pushes the core 4 laterally into engagement with the inner wall of the can 1. The desired frictional resistance is then furnished in large part by the can. The plunger 100 pushes the core into the can until it is released from the finger 16, when it drops to the bottom of the can. If electrolyte is present in the can, the core may be released as soon as it touches the liquid, so that it settles slowly by gravity to the can bottom, the elec-

trolyte welling up between the core and the can.

This electrolyte is, of course, corrosive, and there is disadvantage in having it splash or spill on the outside of the can or on operative parts of the machine itself. There is advantage in having the plunger 17 start downward with a relatively rapid movement, and then gradually slow up in its speed of travel as the core approaches and enters the surface of the electrolyte in the can. This result is attained by properly timing the movements of core holder 10 and plunger 17 and by regulating their speed of travel so that at the time the core leaves contact with the immovable jaw of the holder, the core is traveling at a slow rate. Thereafter the downward travel of the core can be very slow to permit the electrolyte to well up around the core without squirting or spilling out of the can. Friction engagement between the core and finger 16 and between the core and the opposed inside of the can keeps the core from dropping unrestrained until after it enters the electrolyte. Then it settles by gravity. The subsequent step of putting on the usual paper washer centers the core in the can.

These cores of molded mix are comparatively fragile and therefore subject to mechanical damage if roughly handled. This is especially the case if the core is not covered with cheesecloth or other fibrous envelope. The mechanism above described functions well in inserting the core into the can, and ultimately into the electrolyte, at a speed slow enough to prevent undue squirting or spilling of the electrolyte or mechanical damage to the core, and the core can be in frictional contact with the side of the can until about the time it enters the electrolyte, and can then be released to allow the core to settle slowly by its own weight through the electrolyte to the bottom of the can, the electrolyte meantime welling up around the core to substantially encase the core as shown in Fig. 5.

After the core is released, the core holder and plunger return to their original position (Fig. 1).

It is readily apparent that the apparatus may be so designed that the core may be in frictional contact with the can during the entire or any part of its descent. The duration of frictional contact with the can may be varied by varying the distance to which the core holder is lowered. The closer it comes to the can the shorter the time of frictional contact between the core and the can and the shorter the plunger travel through the holder. The described apparatus gives the minimum frictional contact with the can and the corresponding plunger travel, but various changes in proportions will readily suggest themselves, and various elements of this preferred form of apparatus above described

may be altered without departing from the spirit of my invention as defined by the appended claims.

I claim:

1. In mechanism for inserting a dry cell cathode core into a can, a core-holder with a core-deflecting finger thereon. 70

2. In mechanism for inserting a dry cell cathode core into a can, the combination of a spring actuated core-holding jaw, and a deflector attached to the spring actuated element of said jaw. 75

3. In mechanism for inserting a dry cell cathode core into a can, the combination of a spring actuated core-holding jaw, a deflector attached to the spring actuated element of said jaw, and a plunger movable into said jaw to eject a core therefrom. 80

4. In mechanism for inserting a dry cell cathode core into a can, the combination of a spring actuated core-holding jaw, a deflector attached to the spring actuated element of said jaw, means for feeding said core to said jaw, and means for ejecting said core from said jaw. 85

5. Mechanism for inserting a dry cell cathode core into a can, comprising in combination, a holder for said core positioned above said can and registering therewith, a plunger for ejecting said core from said holder, and a deflector extending downward from said holder, said holder being movable so that said deflector may enter said can. 90

6. In mechanism for inserting a dry cell cathode core into a can, the combination of a spring actuated core-holder, a deflector on the spring actuated section of said core holder, said deflector being so positioned with reference to said core-holder and can that when said core has been ejected against frictional resistance through the bottom of the holder and thereby inserted into said can, said core will be deflected by said deflector to make frictional contact with the inside of said can, and an ejector for pushing said core out of said holder. 100

7. Apparatus for introducing a dry cell cathode into a can of electrolyte without undue splashing of the electrolyte consisting essentially of means for introducing the core into the can at a predetermined speed, and means for thrusting it sidewise in contact with the can and permitting it to move downward at a decreased speed and while in frictional engagement with the side of the can until the electrolyte has welled up to envelope the core. 115

8. Apparatus for inserting a dry cell cathode into a can of electrolyte without undue splashing of the electrolyte consisting essentially of means for inserting said core into said can at a predetermined speed, means for thrusting said core sidewise into contact with the wall of the can, and means for lowering it at a reduced speed while in 120

frictional engagement with the can and ultimately releasing the core and allowing it to settle by gravity to complete the welling up of the electrolyte around the core.

5 9. Apparatus for inserting a dry cell cathode core into a can containing liquid electrolyte consisting essentially of means for inserting said core into said electrolyte slowly to prevent undue squirting of said electrolyte or mechanical damage to the core, said core being in frictional contact with the side of said can during its passage into the electrolyte, and means for releasing said core of its frictional contact with said can after entering said electrolyte and allowing said core to settle slowly to the bottom of said can through said electrolyte by its own weight.

10 10. Apparatus for controlling the speed

of inserting a dry cell cathode core into a can containing liquid electrolyte consisting of means for pushing said core at a relatively high speed against frictional resistance of the can during the first part of the descent into said can and at relatively slow speed while entering the electrolyte.

11. Apparatus for inserting a dry cell cathode core into a can of electrolyte without undue splashing of the electrolyte consisting essentially of means for lowering the core into the can and means for thrusting it sidewise in contact with the can wall and allowing it to move down into the electrolyte while in frictional engagement with said can wall.

35 In testimony whereof I affix my signature.

HANS A. RING.
